UNITED STATES PATENT OFFICE.

JOSEPH P. LEECH, OF BUFFALO, NEW YORK

EXPANDING-REAMER.

1,296,536.

Specification of Letters Patent.

Patented Mar. 4, 1919.

Application filed November 20, 1916. Serial No. 132,459.

To all whom it may concern:

Be it known that I, JOSEPH P. LEECH, a citizen of the United States, residing at 54 Vernon Place, city of Buffalo, county of Erie, and State of New York, have invented a new and useful Expanding Reamer, of which the following is a specification.

My invention relates to expanding reamers.

One of the objects of the invention is to provide a reamer of exceptionally great strength, durability and efficiency.

Another object of the invention is to provide a reamer of this character that is exceptionally easy to adjust, and which is capable of very quick and accurate adjustment.

Another object of the invention is to provide a reamer of this character the cutters of which may be very quickly and firmly secured in any adjusted position, and which will not be accidentally moved out of such adjusted position, even when subjected to the most severe working tests.

Another object of the invention is to provide a reamer of this character with ample clearance for the chips and shavings cut from the side of the hole being reamed.

Another object of the invention is to provide a reamer of this character with oil ducts so arranged as to apply lubricating material to the cutting edges of the cutters.

I attain the foregoing objects by the mechanism illustrated in the accompanying drawings, in which,—

Figure 1 is a side elevation view of my improved reamer. Fig. 2 is a transverse sectional view, taken on the line 2—2 of Fig. 1. Fig. 3 is a fragmental sectional view taken on the line 3—3 of Fig. 2. Fig. 4 is a fragmental sectional view taken on the line 4—4 of Fig. 2. Fig. 5 is a perspective view of one of the cutters or blades.

In these drawings, in which similar reference characters correspond to similar parts throughout the several views, the body or shank of the reamer is designated by the reference character 10, and is formed with oppositely disposed longitudinal slots 11 into which are normally seated the blades or cutters 12.

The bottoms of the slots or grooves 11 form seats for the cutters respectively, and these seats or groove bottoms are inclined inward and forward or toward the center of the working end of the reamer. The metal

between these diametrically opposed grooves forms a wedge which tends to, and does at times, force the cutters 12 farther apart, as hereinafter explained.

Set-screws 13 are seated and screw-threaded in screw-holes 14 in the shank 10. These set-screws are preferably headless and of a length to be sunk beyond the outer surface of the shank when in use. These screws are each preferably formed with a non-cylindrical socket, so as to receive a suitable wrench for loosening and tightening them.

The working face of each cutter or blade 12 is provided with a longitudinal tapering groove, the taper extending from end to end and being convergent in the direction of the cutting end of the blade. This groove in each cutter or blade is less deep at its narrow end than at its wide end. Each blade or cutter is wider at its cutting end than at its other end, and the base of each of these cutters is formed with a wedge-rib 16 inward of the tapering groove. The blades are securely held in any adjusted position in the grooves or ways 11 by the conical points of the set screws bearing against the outwardly inclined sides of the wedges or wedge-ribs 16, or within the grooves 15. These wedge-ribs being inclined laterally, and the points of the set screws being conical, there is an obvious tendency for the screws, when tightened, to draw the respective blades toward the axis of the reamer shank and thereby increase the frictional engagement of the cutter blades with their seats, the bottoms of the grooves 11, and thereby offset the tendency of the working pressure to cause the blades to recede from the working end of the shank. This tendency to recede is, moreover, offset by the wedge-rib of each cutter.

A third element that offsets the tendency of the cutters to recede is the wedge-shaped section of the cutter, longitudinally through the groove 15, (the groove being deeper at its wide end, as shown in Fig. 4), and a fourth element that offsets this tendency to recede is a screw 17, seated in the screw-hole 18, of the shank 10, and having its head engaged with the notches 19 of the cutters.

The shank 10 is counterbored at 19 to allow the head of the screw 17 to rotate and move axially therein; so the screw-head is protected against becoming accidentally burred, and it will always rotate easily through the notches 19. By means of this screw 17, the cutters may be simultaneously

and equally adjusted in either direction along the grooves or ways 11, and when so adjusted they are moved nearer together or farther apart, at will, by the wedging action of the wedge-shaped section 21 of the reamer shank. After being suitably adjusted, the blades 12 are secured in adjusted position by tightening the set screws 13. By loosening these set-screws, without removing them, the cutter blades may be removed, individually, so as to be sharpened or replaced. When the blades have been ground away beyond the notches 19, they may still be used, by extending or removing the screw 17, for 16 they may be individually adjusted by hand, and the set-screws are amply efficient to prevent disadjustment.

In order to provide ample clearance and accommodation for the shavings or cuttings of metal being reamed, the grooves 11 are considerably longer than the blades seated therein, so that a deep pocket is provided back of each cutter blade 12, as shown at 22, Fig. 4. The shank is also cut away at 25 23, on opposite sides of the shank and in front of the cutting edges 24 and communicating with the pockets 22, so as to provide a passage-way for the cuttings, leaving the cutting edges, to enter the pockets. The 30 cut-away portions or recesses 23 are also extended back beyond the pockets 22, so as to auxiliate the pockets in accommodating the cuttings.

The side of each groove 11 back of its 35 cutter blade is higher than the side in front of the same, so as to effectively and rigidly support said cutter blade in its seat.

The shank 10 is hollow throughout its length, except where closed by the screw 17, 40 and oil ducts 25 communicate with the interior chamber or bore of the shank, so that the reamer is rendered self lubricating.

The face of each cutter or blade is indented at 26, so that the adjacent curved 45 cutting edge is inclined forward of (or has a "lead" with relation to) the part of the working face that supports said curved cutting edge. The plane portion of the working face of each cutter coincides with a plane 50 which is common to such plane portion of both of said cutters, and this plane also coincides with the axis of rotation of the reamer. It will, therefore, be seen that if a diametrical line be drawn coincident with 55 the bottoms of the depressions 26, the curved cutting portions of the cutters 12 are considerably forward or in lead of said diametrical line, and said depressions are inclined outwardly, and in the direction of 60 working rotation, from said diametrical line; that is, in the direction of the arrow in Fig. 2.

The blades or cutters 12 being imperforate, are much stronger and less expensive 65 than are the perforated blades of known

construction. They are also more easily removed and replaced, as the set-screws or locking screws do not need to be removed, but merely loosened.

What I claim as my invention is:

1. A reamer blade formed with a cutting edge and with a groove extending longitudinally of said cutting edge and varying in depth at different points throughout its length.

2. A reamer blade formed with a face having a cutting edge at one side and having therein a groove the depth of which varies throughout its length.

3. A reamer blade formed with a grooved working face and with a rib and with a surface which forms one side of the groove of said working face while also forming one side of said rib and which is inclined with relation to said working face.

4. A reamer blade formed with a grooved face and a wedge-shaped rib and with a surface inclined with relation to said face and forming a side of said rib and a side of the groove of said face.

5. A reamer blade formed with a grooved working face and a wedge-shaped rib and with a surface inclined with relation to said working face and forming a side of said rib and also forming a side of the groove of said working face.

6. A reamer blade having its working face formed with a cutting edge at one side and ribs at its opposite side and with a groove having one of its sides inclined with relation to the portion adjoining said cutting edge, this inclined portion also forming one side of said rib.

7. A reamer blade formed with a cutting edge at one side and with a notch in its opposite side, and with a groove between the cutting edge and the notch and extending longitudinally of said cutting edge.

8. A reamer blade formed with a cutting edge and with a wedge-shaped element extending longitudinally of said cutting edge and having a notch therein.

9. In a reamer, the combination of a shank formed with grooves the bottoms of which converge toward the working end of the shank, a plurality of reamer blades each formed with a groove the depth of which varies at different points in its length and each of said blades being seated within one of said grooves of the shank, and set screws having threaded engagement with the shank and each positioned for frictional and clamping engagement within the said groove of one of said reamer blades.

10. The combination with a reamer blade formed with a notched rib having an inclined side, of a reamer shank formed with a groove inclined toward the front end of the axis of rotation of the shank and constituting a seat along which said blade is

adapted to be adjusted, an adjusting screw engaging with the notch of said rib and operable to move said blade along said seat to different positions of adjustment, and a set screw having a tapering point normally bearing upon the inclined side of said rib so as to securely bind the blade in frictional engagement with the seat.

11. The combination of a reamer shank 10 formed with an oil chamber and with converging blade seats on opposite sides of said oil chamber, and with oil feed ducts communicating with said oil chamber, a plu-

rality of reamer blades each formed with a notch and with a cutting edge and being 15 normally seated in one of said blade seats in such position that one of said oil feed ducts opens in front of its cutting edge, means engaging with the notch of each blade for moving the blade to different positions of 20 adjustment along its seat, and means for clamping each said blade securely against its respective one of the said converging blade seats.

JOSEPH P. LEECH.
